UNITED STATES PATENT OFFICE.

HENRY HARTUNG, OF BALTIMORE, MARYLAND.

SOFA-BED.

1,301,936.

Specification of Letters Patent. Patented Apr. 29, 1919.

Application filed February 3, 1917. Serial No. 146,404.

To all whom it may concern:

Be it known that I, HENRY HARTUNG, a citizen of the United States, residing at Baltimore city, in the State of Maryland, 5 have invented a certain new and useful Sofa-Bed, of which the following is a specification.

My invention relates to improvements in sofa beds, and the object of my improvement 10 is the providing of an improved sofa bed capable of being opened out to full bed length by one operation.

A further object of my improvement is the providing in a sofa bed of means of 15 closing the same from full bed length by one operation.

A further object of my improvement is the providing of means of locking the frame thereof in open position.

20 A further object of my improvement is the providing in a sofa bed of the character described, means of counter weighting the moving parts.

And a further object of my improvement 25 is the providing of means of utilizing the back as a foot in the open position of a sofa bed.

With the foregoing and other objects in view, my invention consists of the novel construction, combination and arrangement of 30 parts, as herein specifically described and illustrated in the accompanying drawings, wherein is shown the preferred embodiment of my invention, but it is understood that 35 changes, variations and modifications can be resorted to which come within the scope of the claim hereunto appended.

In the drawings of the herein described embodiment of my invention, Figure 1 40 shows a perspective view of my improved sofa bed, open ready to receive the mattress. Fig. 2 is a sectional view of the sofa bed taken through "A B" of Fig. 1, when the bed is in a closed position. Fig. 3 is a 45 sectional view of the sofa bed taken through "A B" of Fig. 1, when the bed is in a closing position, showing particularly the joints of the mattress frame, and Fig. 4 is a sectional view of the sofa bed taken through 50 "A B" of Fig. 1 in the open position as shown in said figure.

Similar numerals refer to similar parts throughout the several views.

1 is a base. 2 is the seat. 3 is the back. 55 4 are the arms. 5 is the rear section of the mattress frame. 6 is the intermediate sec-

tion of the mattress frame. 7 is the front section of the mattress frame. 8 is the fabric in the mattress frame.

9 is a pivot support secured to arms 4 to 60 which is secured pivot 10. 11 is a slotted plate in which operates pivot 10 and which is secured to rear section 5 of the mattress frame.

On seat 2 is a member 12 to which is pivotally mounted intermediate section 6 of the mattress frame at 13 and at 14 forms a support, and locking device for the said intermediate section preventing the mattress frame from folding when the bed is in open 70 position.

15 is a guide member secured to seat 2 in which the front section 7 of the mattress frame slides and oscillates.

The mattress frame sections 5, 6 and 7 75 are pivoted together at 16 and 17, preferably on the edge of the mattress frame, thus at a distance from the fabric, and to permit of the folding of the mattress and bedding within the mattress frame and its fabric when in position.

Mattress frame 5, 6 and 7 is preferably made out of angle iron as shown in the drawing and pivoted at 16 and 17 so as to break in one direction only, thus when they 85 are out in open position will not open upward beyond a straight line.

18 is a brace for intermediate section 6. 19 is the hinge, operatively connecting seat 2 and base 1. 20 is a counter balance spring 90 or means of counterbalancing the moving parts, secured to member 12 at one end, and as shown in the drawings, a spring secured to base 1, to counter balance the weight of seat 2 and back 3 in the operation 95 of opening and closing.

The operation of my invention is as follows.

Starting in the open position as shown in Fig. 1, with the mattress and bedding 100 omitted, raising back 3 causes the mattress frame to first break at 16 and slot 11 to slide and turn on pivot 10, then to break at 17 and intermediate section turns on pivot 13 locking member 14 giving away to allow 105 this movement and then front section 7 oscillates and slides in guide member 15 until seat 2 is in closed position.

Having thus described my invention, what I claim and desire to secure by Letters Patent is:

A sofa bed comprising a frame, a seat

and back pivotally mounted to said frame, a mattress frame consisting of a plurality of parts operatively secured together by joints preventing buckling of the parts in 5 bed position, an intermediate part pivotally mounted to a member relatively stationary with reference to said seat and back, a locking device on said member securing said intermediate section in open position when 10 the bed is in open position, and means of

permitting the other sections of the mattress frame to adjust themselves with reference to the main frame and seat in opening and closing and co-operating with said locking device in holding them secure at the limits 15 of movement.

HENRY HARTUNG.
